UNITED STATES PATENT OFFICE.

JOHN F. GAIL, OF KENOSHA, WISCONSIN, ASSIGNOR TO THE SIMMONS MANUFACTURING COMPANY, OF KENOSHA, WISCONSIN, A CORPORATION OF WISCONSIN.

TUBE-BENDING MACHINE.

957,200.

Specification of Letters Patent. Patented May 10, 1910.

Application filed July 19, 1909. Serial No. 508,341.

To all whom it may concern:

Be it known that I, JOHN F. GAIL, a citizen of the United States, residing at Kenosha, in the county of Kenosha and State of Wisconsin, have invented certain new and useful Improvements in Tube-Bending Machines, of which the following is a specification.

My present invention relates to machines or appliances for bending pipes or tubes such, for example, as are used in metal bedsteads, the preferred embodiment of the invention being a machine capable of producing in such pipe or tube a plurality of bends at the same time, whereby the pipe or tube forming the main portion of the head or foot of a metallic bedstead may be readily bent to shape. The novel mechanism for producing the bending is largely automatic in its operation, suitable rotary or traveling benders turning around curved forms to produce the bends in the pipe, such benders automatically returning to their original position, at which time a brake is applied to the operating mechanism to stop the parts.

Various features of novelty and improvement will be made apparent from the following detail description taken in connection with the accompanying drawings, which illustrate a desirable embodiment of the invention.

Referring to the drawings—Figure 1 is a plan view of my improved machine; Fig. 2 is a front elevation of the same, certain parts being broken away to more clearly illustrate the construction; Fig. 3 is an enlarged end view of the appliance; Fig. 4 is an enlarged cross-section on line 4—4 of Fig. 1; and Figs. 5 and 6 are face and edge views, respectively, of a lever controlling the actuation of the clutch mechanism.

The machine includes a comparatively long main frame 10 supported on suitable legs or standards 11, and at the head or left-hand end of the machine there is provided a stationary support or table-top 12, the machine being also equipped with a carriage 13 adjustable longitudinally of the frame, that is, toward and from the head support 12, by a screw 14 running lengthwise of the machine and having a threaded engagement with the carriage 13, this screw at the tail end of the machine being supplied with an operating or turning handle 15. It will,

therefore, be obvious that by turning such handle the position of the carriage or movable support 13 may be readily varied or adjusted. The head support or block 12 has a stationary vertical shaft or stud 16, to which is fastened a round form 17 concave on its edge at 18, as indicated in Fig. 4, to conform to the external curvature or convex surface of the pipe to be operated upon. Rotatable on this shaft or stud 16 below the form 17 I provide an oscillatory toothed or gear sector 19, projecting from the upper face of which is a shaft or pin 20 on which is mounted a rotatable bender 21 likewise grooved on its edge at 22, the pipe or tube 105 to be bent being adapted to be received between the form 17 and roller bender 21, as indicated in Fig. 1. A pinion 23 on the top end of a vertical shaft 24 meshes with the sector 19, the shaft 24 bearing at its lower end a comparatively large worm wheel 25 meshing with the teeth of which is a worm 26 on a main shaft 27 extended lengthwise of and in front of the frame 10, being rotatable in suitable bearings 28, 29 and 30. An adjustable carriage 13 is equipped with a corresponding bending mechanism, the same having a stud or shaft 31, a grooved form 32, a rotary sector 33, a roller bender 34, and a vertical shaft 35 having a pinion 36 at its upper end and a worm-wheel 37 at its lower end, the latter co-acting with a worm 38 on the main shaft 27 and adjustable longitudinally thereof so as to maintain its proper engagement with the worm-wheel 37 in all adjusted positions of the tail carriage. This worm 38 is desirably splined on the shaft 27 and capable of being slid lengthwise thereof, being preferably maintained in proper position by a recessed casting 39 overlapping its opposite ends and secured to the movable carriage 13, bars 40 at both the front and back of the frame riding in guideways 41 on outstanding flanges of the frame, as is clearly shown in Fig. 4. A similar construction is also provided for the head worm 26 as illustrated. It will, therefore, be apparent that as the carriage 13 is shifted the worm will be also slid on its shaft 27 and will be maintained at all times in proper relation with its co-operating worm-wheel 37.

The main shaft 27 is intended to be driven from a driving shaft 42 which is connected to the main shaft by a crossed belt 43 engaging a pulley 44 fixed to the driving shaft 110

and a pulley 45 loose on the shaft 27. This driving shaft 42 is also joined to the main shaft by a plain belt 46 encircling a pulley 47 rotatable with the shaft 42 and another 5 loose pulley 48 from the shaft 27. The pair of loose pulleys 45 and 48 are each supplied with an internal clutch mechanism 49 and 50, respectively, either of which may be rendered operative or active by a sliding clutch 10 sleeve 51 mounted on the shaft 27 and provided at its opposite ends with conical or inclined surfaces. This clutch sleeve is intended to be operated by a lever 52 fulcrumed on the floor at 53 and supplied with a strap 15 54, passing around the sleeve, the lever and strap being supplied with the usual internal pins projecting into an annular groove on such sleeve, this construction being old and well known in the 20 art. The top end of this lever 52 is pivoted to a rod 55 which passes through an eye 56 of a bell-crank lever 57 loosely fulcrumed on shaft 24 below the pinion 23, the shorter arm 58 of such lever lying in 25 the path of travel of a lug 59 extending downwardly from the bottom face of the gear sector 19, as is indicated in Fig. 1. On rod 55 on opposite sides of the eye 56 of lever 57 I fasten a pair of collars 60 and 61, 30 the rod 55 being also equipped with an outstanding handle 62.

To the front of the machine frame I secure an air chamber or casing 63 having a forward extension 64 equipped with a stuffing box 65 through which slides the stem 66 of a piston 67 in the chamber, the latter near its right-hand end having an air exhaust port 68. As is illustrated, the forward end of the stem 66 is connected to the 40 lever 52 by a link 69. Compressed air is admitted to a suitably-supported valve casting 70 (Fig. 1) through a supply pipe 71, and when the valve, of which the stem 72 is shown, is open the air passes through the 45 connecting pipe 73 and a hose 74 to the extension 64 and casing or chamber 63. Adjacent to the valve and operable on the spring-pressed rod or stem 72 of the normally closed air valve is a bell-crank 75 50 equipped at its end with a roller 76 adapted to co-act with a finger 77 carried by the sector 19.

At its tail end the main shaft 27 is equipped with a brake wheel 78 encircled 55 by a brake strap or band 79, one end of which is fixed to a standard or support at 80, the other end being connected to one arm of a bell-crank lever 81 suitably fulcrumed at 82, the other end 83 of such bell-crank lever being connected to a brake rod 84 extended longitudinally of the machine in front of its main frame. Such rod is 60 65 slidable in a bearing 85, being connected thereto by a coil contractile spring 86 tending to shift the rod and bell-crank to loosen

the brake strap on the brake wheel. Also fastened to this brake rod are two collars 87 and 88, against the former of which bears a lever 89 having an upstanding arm 90 in the path of travel of a block 91 on the 70 bottom face of sector 19, and a downwardly-extended arm 92 bearing a roller 93 in its bottom bifurcated end. A torsion spring 94 encircles the brake rod between the collar 88 and the lever 89, acting to maintain the 75 lever against the collar 87 and to swing the lever inwardly, as is indicated in Fig. 4, into the path of travel of block 91.

A pair of bent arms 95 connected together at the front of the machine by a rod handle 80 96 are pivoted at the back of the machine at 97 on depending ears 98 of the supports 12 and 13, respectively, the upwardly bent portion 99 of the head lever 95 being adapted in its upward swinging to engage the 85 roller 93 of the lever 89 and rock the latter on the brake rod 84 sufficiently against the action of spring 94 to move the arm or portion 90 of the lever out of contact with the block 91 of the sector, whereupon the contraction of spring 96 shifts the brake rod and attached mechanism to throw off the 90 brake. The two arms 95 have loosely connected thereto a pair of sliding bars 100 movable vertically in suitable guideways in 95 the support 12 and carriage 13, each bar 100 bearing at its top end a recessed holder 101 adapted in its raised position to receive in its notch or cavity 102 the pipe or tube to be bent. In order to compensate and allow 100 for the adjustment movement of the carriage 13 the rod handle 96 is made comparatively long, passing through apertures in the front ends of the levers 95 and being 105 slidable in such apertures to compensate for the adjustment of the arm 95 mounted on the carriage 13.

To the support or table 13 is secured a longitudinally extended bar such as an angle bar 103, adjustable lengthwise of which I 110 provide a gage 104. In addition the teeth of the pinions and sectors may be inclosed by suitable guards or casings 106, which are shown in some of the figures and omitted from the others for the sake of clearness. 115

The operation of this improved mechanism is practically as follows: For the rapid bending of the pipes or tubes to be used in the manufacture of bedsteads, two workmen can be advantageously employed with this machine, one of whom, located at the tail end of the machine, that is the right-hand end as viewed in Fig. 1, inserts the pipe or tube 105 to be bent between the round formers 17 and 32 and the roller benders 21 and 34, while the latter are in the position indicated in Fig. 1, until such pipe or tube strikes the stop 104 which properly positions the tube for the correct bending. The other workman, standing at the front of the 120 125 130

machine, then lifts the handle 96 and during the raising of the head lever or arm 95 the latter strikes the roller 93 of the lever 89, rocking the same on the brake rod to remove the portion 90 of the lever from engagement with the block 91, whereupon spring 86 shifts the brake rod and attached parts to the left, throwing off the brake. Continued movement of the handle 96 raises the recessed holders 101 into such position that they receive in their cavities or seats 102 the portions of the pipe adjacent to the pair of forms, and during the subsequent bending operation prevent distortion or improper bending of the piece operated upon. Having lifted the handle, thrown off the brake, and raised the holders, as indicated, the workman by grasping the clutch handle 62 pushes the lever 52 to the left, thereby rendering the clutch 49 active and coupling the rotating pulley 45 to the shaft 27, causing the rotation of the worms 26 and 38, worm-wheels 25 and 37, shafts 24 and 35, pinions 23 and 36, toothed sectors 19 and 33, and the pair of roller benders 21 and 34, which as they turn or rotate about the formers 17 and 32 bend the ends of the tube or pipe into the dotted line positions indicated in Fig. 1. The parts of the mechanism are so related that when the desired bending has been accomplished the cam finger 77 will strike the roller 76 of the bell crank 75, rocking the latter so as to open the valve 70 and permit the passage of compressed air from the supply pipe 71 through the pipe and hose 73 and 74 to the casing or chamber 63, where it acts upon the front face of the piston 67 to shift the latter and the clutch lever 52 to the right sufficiently to render the clutch 49 inoperative and couple the reversely-rotating pulley 48 to the shaft 27 by the other clutch 50; the air then escaping through the port 68. This unclutching and clutching of the other pulley results in the reverse rotation of the shaft 27, the sectors 19 and 33, the roller benders which they carry, and the intermediate mechanism, the workman quickly extracting the bent tube from the forming members before reverse movement thereof begins. When the sector 19 reaches its initial or original position, the block or finger 59 strikes the short arm 58 of the bell crank lever 57, which was turned somewhat by the engagement of collar 60 therewith during the right-hand shifting of the lever 52 by means of the air-actuated piston, rocking the bell crank lever sufficiently to shift the rod 58 through the medium of the fixed collar 60 so as to bring the clutch sleeve 51 into intermediate or neutral position, that is, the position corresponding to the inactive condition of both clutches, which of course results in a cessation of the rotation of the parts. Also when this sector 19 reaches its

original position the block 91 strikes the arm 90 of the lever 89, thereby shifting the brake rod 84 and other parts to the right against the action of spring 86, throwing on the brake strap and abruptly stopping the rotation of the shaft 27, it being understood, of course, that before the workman extracted or pulled out the bent tube or pipe he permitted the levers 95, the holders 101, and the handle 96 to drop, which downward movement freed the lever 89 so as to permit the torsion spring 94 to swing the upper arm 96 of the lever into the path of travel of the block 91. The parts now remain in this position until the first workman inserts another pipe or tube and the operations above described are then repeated, the tubes being bent and finished with considerable celerity.

Whereas I have herein set forth with some degree of particularity the minor details of construction of my preferred embodiment of the invention, it is nevertheless to be understood that this invention is not limited to the precise structural features shown, since they may be modified within comparatively wide limits without departure from the substance and essence of the invention.

I claim:

1. In a machine of the character described, the combination of a pair of forms, a bender adapted to rotate about each of said forms, a pair of manually-actuated sliding notched holders adapted to engage the tube to be bent adjacent to both of said forms to prevent distortion of the tube during the bending operation, and means to simultaneously rotate said benders whereby a tube introduced between said forms and benders may be bent in two places at the same time, substantially as described.

2. In a machine of the character described, the combination of a pair of forms, a bender adapted to rotate about each of said forms, means to simultaneously rotate said benders, whereby a tube introduced between said forms and benders may be bent in two places at the same time, means to automatically stop the turning of said benders and return them to their initial positions after the completion of a predetermined amount of angular turning, a brake for said rotating means, and means to automatically throw said brake into action when said benders reach their initial positions, substantially as described.

3. In a machine of the character described, the combination of a pair of forms, a bender adapted to rotate about each of said forms, means to simultaneously rotate said benders, whereby a tube introduced between said forms and benders may be bent in two places at the same time, movable holders to engage said tube adjacent to said forms to

- prevent distortion of the tube during the bending operation, means to automatically stop said benders and return them to their initial positions after the completion of a predetermined amount of angular turning, a brake for said bender rotating means, means to automatically throw said brake into operation when said benders reach their initial positions, and means to throw said brake out of action when said holders are moved into tube engaging position, substantially as described. 5
4. In a machine of the character described, the combination of a pair of forms, a pair of benders adapted to rotate about said forms, a driving shaft, driving connections between said shaft and benders, oppositely rotating pulleys loosely mounted on said shaft, clutches to operatively connect said pulleys to said shaft, means whereby one of said clutches may be rendered active to cause the simultaneous bending turning of said benders about their respective forms, a compressed fluid means to render said clutch inactive and the other clutch active upon completion of the required bending turning of said benders, means movable with one of said benders to control the actuation of said air operated clutch-controlling means, and means to render said second clutch inactive when the benders return to initial position, substantially as described. 10
5. In a machine of the character described, the combination of a form, a bender, means to turn said bender around said form whereby to bend a tube introduced between said form and bender, a brake for said turning means, means to automatically stop the bending turning of said bender and return it to initial position after the completion of a predetermined angular turning, and means to automatically throw said brake into action when said bender reaches its initial position, substantially as described. 15
- 45 6. In a machine of the character described, the combination of a form, a bender, means to turn said bender around said form to bend a tube introduced between said form and bender, means to automatically stop the bending turning of said bender and return it to initial position after the completion of a predetermined angular turning, a brake for said bender rotating means, means to automatically throw said brake into action when said bender reaches its initial position, a 20
- holder movable to engage the tube to be bent adjacent to said form to prevent distortion of the tube during the bending operation, and means whereby during such movement of the holder said brake is thrown out of action, substantially as described. 25
7. In a machine of the character described, the combination of a rotatable frame, a former carried axially on said frame, a bender pivoted to said frame to be bodily carried about the former upon rotation of the frame, forward and reverse drive mechanism for said frame, means for rendering the forward drive mechanism effective, and pneumatic mechanism operative at the end 30 of the forward movement to set the driving mechanism for reverse operation. 35
8. In a machine of the character described, the combination of a rotatable frame, a former carried axially on said frame, a bender pivoted to said frame to be bodily carried about the former upon rotation of the frame, forward and reverse drive mechanism for said frame, means for rendering the forward drive mechanism effective, pneumatic mechanism operative at the end of the forward movement to set the driving mechanism for reverse operation, and means automatically controlled at the end of the reverse movement of the frame to stop the 40 frame. 45
9. In a machine of the character described, the combination of a rotatable frame, a former carried on said frame, a bender pivoted to said frame to travel about the former upon rotation of the frame, forward and reverse drive mechanism for said frame, clutch mechanism for controlling the connection of the forward and reverse drive mechanism with the frame, means for initially moving the clutch mechanism to connect the forward driving mechanism in service, pneumatic mechanism controlled by the forward rotation of the frame to move the clutch mechanism from the forward driving mechanism and into engagement with the reverse driving mechanism, and means automatically controlled by the reverse movement of said frame for moving the clutch mechanism to neutral position to disconnect both 50 drive mechanisms from the frame. 55
